FOOT ARCH SUPPORT

Edward E. Dettelbach, Los Angeles, Calif.

Application May 10, 1932. Serial No. 610,375

4 Claims. (Cl. 36—71)

This invention relates to improvements in supports for the arch portion of the feet.

The general object of this invention is to provide an improved foot arch supporting device 5 adapted to be placed in a shoe.

A further object of the invention is to provide a shoe with an arch support which is self aligning and allows free movement of the foot while supporting the arch portion thereof.

10 Other objects and the advantages of this invention will be apparent from the following description taken in connection with the accompanying drawings wherein:

Fig. 1 is a top plan view of a shoe showing my 15 improved arch support operatively positioned therein and showing it in a raised position before the foot has been placed in the shoe.

Fig. 2 is a section taken on line 2—2 of Fig. 1.

Fig. 3 is a view similar to Fig. 2 showing the 20 position of the arch support after the foot has been placed in the shoe.

Fig. 4 is an enlarged top plan view of the arch support.

Fig. 5 is an enlarged rear view of the arch 25 support.

Fig. 6 is a section taken on line 6—6 of Fig. 5.

Fig. 7 is a view similar to Fig. 6 showing a modified form of support member for the arch support.

30 Fig. 8 is a central longitudinal plane section through a modified form of arch support.

Fig. 9 is a fragmentary view similar to Fig. 8 showing the supporting member in an extended position.

35 Fig. 10 is a view similar to Fig. 6 showing a further modified form of supporting member for the arch support.

Fig. 11 is a view similar to Fig. 10 showing a 40 still further modified form of supporting member.

Fig. 12 is a fragmentary rear view of the device shown in Fig. 11.

Referring to the drawings by reference character, I have indicated my improved foot arch supporting device generally at 10. In Figs. 1, 2, 45 and 3, I have shown the device 10 as operatively positioned in a shoe 12 which includes a sole 13, an upper portion 14, a heel 15 and an insole 16. As shown the arch supporting device 10 includes 50 a metal or other plate 18 and a supporting bracket 19. The bracket 19 is shown as formed of a single length of metal rod bent back upon itself and includes a foot portion 20 and an upstanding portion 21 bent out at an angle to the 55 foot portion 20. The end portions of the angular

portion 21 are bent at an angle thereto as at 21' in Fig. 5 and are rotatably mounted in bearing members 22 secured to the rear face of the plate 18 as shown in Fig. 5. In longitudinal and transverse cross section the plate 18 is shaped 60 to conform to the shape of the portion of the foot the device is adapted to engage and the face and edges of the plate 18 are preferably covered with leather or other suitable material as indicated at 23.

In use the device 10 is placed in the shoe at a locality where it will, when the foot is placed in the shoe, be positioned below the arch of the foot. When positioning the device 10 in the shoe the foot portion 20 of the supporting bracket 19 70 is preferably placed between the insole 16 and the sole 13 of the shoe as shown in Figs. 2 and 3. Before placing the foot in the shoe the plate 18 is turned upward as shown in Figs. 1 and 2 and then the foot is placed in the shoe. As the foot 75 engages the plate 18 it moves it downward to the position shown in Fig. 3. As the foot is thus placed in the shoe and engages the plate 18 the plate 18 is automatically aligned in correct relation to the foot. When walking the hinged connection of the supporting bracket 19 to the plate, at 22, allows the plate 18 to move with some motion of the foot and the foot portion 20 of the supporting bracket 19 has a slight rocking movement between the insole 16 and the sole 13 there- 85 by allowing the plate 18 to rock with other motions of the foot.

In Fig. 7 I have shown a supporting bracket 25 which is similar to the supporting bracket 19 with the exception that, adjacent the juncture of 90 the foot portion of the bracket and the angular portion, each of the sole members of the foot portion thereof are bent upwardly to form a raised portion 26. When the device is positioned in a shoe and is placed therein the lower portion of the plate 18 engages the raised portion 26 to support the lower end of the plate 18 in a higher position than it would be supported by the bracket 19. The height of the raised portion 26 of the bracket 25 may be changed to support 100 the plate 18 in various positions to accommodate different foot arches.

In Figs. 8 and 9, I have shown another modified form of supporting bracket indicated at 27. As shown the bracket 27 includes two similar 105 metal rods 28 each of which includes a foot portion 29 and an angular portion 30 which is pivotally secured to the plate 18 by a bearing member 31 similar to the bracket 19. The ends of the rods forming the foot portions 29 are bent 110

in opposite directions as at 32 to form prong portions. A metal loop 33 surrounds the rods 28 and is normally positioned adjacent the prong portions 32 as shown in Fig. 8. When the foot portions 29 of the bracket 27 are positioned between the insole and the sole the loop 33 engages the insole and remains stationary while the friction caused by forcing the rods 28 of the foot portions 29 into position spreads the rods 28 apart as shown in Fig. 9 thus making it more difficult for the device to become accidentally dislodged.

In Fig. 10 I have indicated a further modified form of supporting bracket generally at 35. As shown the bracket 35 includes a socket member 36 secured to the plate 18 and a threaded shank 37. The shank 37 includes a spherical portion 38 which is positioned in a socket recess 39 provided in the socket member 36. An internally threaded eyelet 40 is positioned in an aperture 41 provided in the sole 13 of the shoe and the shank 37 is positioned in the eyelet and extends through an aperture 42 provided in the insole 16. By rotating the shank 37 the plate 18 may be either lowered or raised to the desired position and a lock nut 43 provided on the shank 37 is adapted to retain the shank in the position to which it has been moved. The ball and socket connection between the plate 18 and the shank 37 allows the plate 18 to move freely with all motions of the foot.

In Figs. 11 and 12, I have indicated a still further modified form of supporting bracket generally at 45. As shown the bracket 45 is made from a flat piece of metal and like the bracket 19 includes a foot portion 46 and an angular portion 47. The angular portion 47 includes a bearing portion 48 in which a pin 49 is positioned. The pin 49 is further positioned in bearing portions 50 which are outstruck from the plate 18. On the foot portion 46 of the bracket, I provide a boss 51 which includes a threaded aperture 52 in which a threaded stem 53 is positioned. The threaded stem 53 extends through an aperture 54 provided in the sole 13 and a lock nut 55 is positioned on the stem 53 adjacent the underface of the sole 13. By rotating the stem 53 to move up or down the plate 18 may be set in various adjusted positions to accommodate different types of foot arches.

From the foregoing description it will be apparent that I have provided a novel foot arch support which is simple in construction and highly efficient in use.

Having thus described my invention, I claim:

1. In combination with a shoe including a sole, an arch supporting device, said arch supporting device including a plate and a plate supporting bracket, said plate being shaped to conform to the shape of a foot adjacent the inner

longitudinal arch portion thereof, said bracket being formed of metal bent to include a foot portion and an angularly arranged portion, said angular portion being hinged about a horizontal axis to the center of the rear face of said plate, said device being positioned in said shoe at a position wherein when a foot is placed in said shoe said plate will engage the inner longitudinal arch of said foot, and said plate will swing about said horizontal axis into an adjusted position.

2. In combination with a shoe including a sole, an arch supporting device, said arch supporting device including a plate and a plate supporting bracket, said plate being shaped to conform to the shape of a foot adjacent the inner longitudinal arch portion thereof, said bracket being formed of metal bent to include a foot portion and an angularly arranged portion, said angular portion being pivotally secured to the center of the rear face of said plate and means positioned on said foot portion to limit the inward swing of said plate about said central pivot, said device being positioned in said shoe at a position wherein when a foot is placed in said shoe said plate will engage the inner longitudinal arch of said foot.

3. In combination with a shoe including a sole, an arch supporting device, said arch supporting device including a plate and a plate supporting bracket, said plate being shaped to conform to the shape of a foot adjacent the inner longitudinal arch portion thereof, said bracket being formed of metal bent to include a foot portion and an angularly arranged portion, said angular portion being pivotally secured to an intermediate portion of the rear face of said plate, and means integral with said foot portion to engage said plate and limit the swing of the plate, said device being positioned in said shoe at a position wherein when a foot is placed in said shoe said plate will engage the inner longitudinal arch of said foot.

4. In combination with a shoe including a sole, an arch supporting device, said arch supporting device including a plate and a plate supporting bracket, said plate being shaped to conform to the shape of a foot adjacent the inner longitudinal arch portion thereof, said bracket being formed of metal bent to include a foot portion and an angularly arranged portion, said angular portion being pivotally secured to the center of the rear face of said plate, said device being positioned in said shoe at a position wherein when a foot is placed in said shoe said plate will engage the inner longitudinal arch of said foot, and said plate will swing about said pivot into an adjusted position.

EDWARD E. DETTELBACH.
